UNITED STATES PATENT OFFICE

95,762

DESIGN FOR A BEVERAGE DISPENSER

Oscar J. Leins, Milwaukee, Wis., assignor to Milwaukee Gas Specialty Company, Milwaukee, Wis., a corporation of Wisconsin

Application September 10, 1934, Serial No. 53,243

Term of patent 14 years

To whom it may concern:

Be it known that I, Oscar J. Leins, a citizen of the United States, residing at Milwaukee, in the county of Milwaukee and State of Wisconsin, have invented a new, original, and ornamental Design for Beverage Dispensers, of which the following is a specification, reference being had to the accompanying drawing, forming a part thereof, and in which the figure is a perspective view of a beverage dispenser showing my new design.

I claim:

The ornamental design for a beverage dispenser as shown.

OSCAR J. LEINS.
